UNITED STATES PATENT OFFICE

LUCIEN LE BLANC, OF DETROIT, MICHIGAN

SIGN

Application filed May 31, 1929. Serial No. 367,460.

The object of this invention is to provide a sign including movable means adapted to receive detachable letters, so that the device may be placed in continuous operation by the use of a motor, and the traveling element may remain constantly in position, but the sign may be changed to suit varying conditions, by removing the letters which may have lost their significance and replacing them with new letters and words.

A further object is to provide means for mounting a flexible belt, driving means for the belt, this belt being provided with openings adapted to receive perforated letters which may also be of flexible material,—lighting means being adapted to throw light rays of any color desired, thru glass plates, and thence on to mirrors or reflecting surfaces, where the subject matter of the sign is exposed for observation.

With the foregoing and other objects in view, the invention consists in the novel construction and arrangement of elements disclosed, it being understood that modifications may be made within the scope of the claims without departing from the spirit of the invention.

In the drawings forming part of this application:—

30 Figure 1 is a view in side elevation, showing a housing with the sign exposed therein, and showing elements of the illuminating means at the top.

Figure 2 is a view in top plan of the structure of Figure 1.

Figure 3 is a view in end elevation.

Figure 4 is a view in longitudinal section on line 4—4 of Figure 2.

Figure 5 is a vertical transverse section on line 5—5 of Figure 1.

Figure 6 shows the traveling element or belt, in top plan, with several perforated letters in position for use.

Figure 7 is a section on line 7—7 of Figure 6.

Figure 8 is a perspective view of one of the letters, which may be of sheet metal, or other substance, such as rubber, facilitating the flexibility of the traveling device as a whole.

The housing includes the bottom 10, the front wall 11 and the ends 12 and 13. The upper portion of the casing or housing includes the frame elements 14, and the latter are grooved as shown in Figure 5, the grooves receiving the outer edges of glass plates 15, which may be of any color desired for a particular sign. The plates may likewise be removable for changing the color. The central plate supporting element is designated 16 and carried thereon are brackets such as 17 adapted to mount electric illuminating means 18.

A vertical central wall 20 provides means for mounting the upper edges of mirrors or reflecting devices 21, 22, the lower edges being supported at 23, and means for adjustment of the angle of inclination being provided if desired.

The traveling element comprises a belt of suitable flexible material designated 25 and this belt is provided with openings 26 which may be of rectangular form, and is further provided with slots at 27, in the edge portions of the belt or traveling device.

This arrangement permits of the insertion of the perforated plates or the like 28, one of which is shown in perspective in Figure 8, the letter I being represented and whereas any suitable material may be used, a plate of sheet rubber of suitable character will promote the flexibility of the entire belt.

The belt 25 is carried around suitable guide rollers such as those shown at 26, the preferred arrangement for a simple device being illustrated in Figure 4, and the roller mounted in the lower central portion of Figure 4 is supported by axle or shaft 28, and a wheel or pulley—rigid with reference to the shaft or with reference to the roller, this rotatable element being designated 29—is driven by belt, chain, or other flexible device 30 adapted to be operated by any suitable motor, an electric motor being usually employed. The driving means are shown conventionally at 31 in Figure 4.

It will be observed that the illuminating means of Figure 5, throw their rays thru the colored plates 15 and the light passes thru the perforated letter plates, and the letters 106

are defined on the reflecting devices 21 and 22 and they are readily observed and read by individuals desiring information regarding a particular play, or regarding merchandise of any character displayed in a store or store window. Since signs may be read from various angles depending upon whether a relatively large sign is employed by an amusement house, or a smaller sign is employed by a merchant, it is desirable to have the reflecting devices 21 and 22 mounted for adjustment, and this adjustment may be provided in any desired manner obvious to those skilled in the art.

15. What is claimed is:—

1. In a device of the class described, a housing, reflecting device therein, illuminating means mounted above the reflecting devices, a traveling element mounted to have one run thereof pass between the reflecting devices and the illuminating element, the traveling element having openings therein and being slotted adjacent to the openings and in a direction parallel with the surface of said element, and removable perforated letter plates for insertion through the slots and in display position opposite the openings.

2. In a device of the class described, a housing, a traveling element mounted therein, said element being provided with openings and being of flexible material, letter plates of flexible material and having rubber-like surface engaging qualities, said plates being adapted for insertion within the body of the traveling element opposite the openings, illuminating means mounted above the traveling element and reflecting means mounted below said traveling element.

3. In a device of the class described, a traveling element, having openings therein extending from one surface to the other surface, and openings communicating with those first named and extending therefrom to one outer edge of the traveling element, and means for imparting motion to the traveling element, flexible perforated letter plates for insertion into the openings first named, and illuminating means positioned to throw rays thru the perforated letter plates.

In testimony whereof I affix my signature.
LUCIEN LE BLANC.
